(57) **CLAIM**

I claim the ornamental design for a hemi-spherical bottle, as shown and described.

DESCRIPTION

FIG. 1 is a front perspective view of a hemi-spherical bottle showing my new design;

FIG. 2 is a back perspective view thereof;

FIG. 3 is a front view thereof;

FIG. 4 is a first side view thereof;

FIG. 5 is a second side view thereof;

FIG. 6 is a bottom view thereof; and,

FIG. 7 is a top view thereof.

The broken line showing of a hemi-spherical bottle is included for the purpose of illustrating only and forms no part of the claimed design.
